(57) **CLAIM**

The ornamental design for a drainage strainer as shown and described.

DESCRIPTION

FIG. 1 is a perspective view of a drainage strainer having a plurality of radial depressions in a top surface thereof.

FIG. 2 is a top plan view of the drainage strainer of FIG. 1.

FIG. 3 is a bottom view of the drainage strainer of FIG. 1.

FIG. 4 is a front view of the drainage strainer of FIG. 1.

FIG. 5 is a rear view of the drainage strainer of FIG. 1.

FIG. 6 is a left side view of the drainage strainer of FIG. 1; and,

FIG. 7 is a right side view of the drainage strainer of FIG. 1.

The broken lines depict portions of the drainage strainer that form no part of the claimed design.

1 Claim, 7 Drawing Sheets
